UNITED STATES PATENT OFFICE.

JAMES SPEAR, OF PHILADELPHIA, PENNSYLVANIA.

FIRE-PLACE HEATER.

SPECIFICATION forming part of Letters Patent No. 362,120, dated May 3, 1887.

Application filed February 13, 1886. Serial No. 191,800. (No model.)

To all whom it may concern:

Be it known that I, JAMES SPEAR, a citizen of the United States, residing in the city and county of Philadelphia, State of Pennsylvania, have invented a new and useful Improvement 5 in Heating-Stoves, which improvement is fully set forth in the following specification and accompanying drawings, in which—

Figure 1 represents a partial side elevation 10 and partial vertical section of a heating-stove embodying my invention. Fig. 2 represents a partial top view and partial horizontal section thereof.

Similar letters of reference indicate corresponding parts in the two figures.

My invention relates to improvements in the class of stoves known as "fire-place heaters," and has for its object the provision of increased heat in the apartment in which the 20 stove is located. For this purpose the stove is set forward to an increased extent, and the drums are similarly disposed, and an outwardly-projecting screen is employed to cover the parts that are advanced, as will be hereinafter 25 fully set forth.

Referring to the drawings, A represents the body of a stove of the order of a fire-place heater, B the jacket at the back of the same, and C the front drums partially within the 30 jacket.

In fire-place heaters of the class as heretofore constructed, a considerable portion of the body of the stove is set back to such extent that much of the heat of the stove enters the jacket and is thus lost to the apartment in which the heater is located, the hot-air drums being also correspondingly set back, the tendency of the arrangement of parts being such that the largest volume of heat enters the 35 jacket and thus supplies the upper apartment, this unequal distribution of heat being objectionable. To obviate this I inclose less of the rear portion of the stove within the jacket, the said jacket being secured to the stove in 40 rear of the front line of the drums located at the side of and in front of the rear line, A', of the stove. The pipes B' are also located farther than usual from the stove, thereby placing the greater portion of the heater in 45 front of the face D of the mantel than heretofore; or, in other words, more of the surface of the stove and drums is within the apartment, and consequently less within the jacket, than is customary in heaters of the class. By 50

this provision the apartment containing the 55 stove receives an increased quantity of heat, while the jacket is sufficiently supplied for the upper apartment. The products of combustion pass from the upper portion of the fire-pot A² into the drums C, which are on 60 both sides of the body of the stove and in front of the rear line thereof, and thence into the chambers B' at the rear of the base of the stove, thence upward into the pipes B', and so escape 65 into the flue. These drums, chambers, and pipes are all within the jacket B, and aid in increasing the quantity of heat within the same, thereby utilizing a large quantity of the heat of the products of combustion which would otherwise be wasted.

The advance of the stove and drums necessarily exposes certain unfinished or rough portions of the top and sides of the former, as well as the top and side portions of the latter. These portions are covered by a screen, E, 75 which projects horizontally forward from the face D of the mantel or breast of the chimney, so as to overhang said portions and conceal the same, it being made of metal of open-work, preferably of the form of an arch, and also 80 serving as a finish to and ornament for the stove, it being evident that while a large portion of the body of the stove which contains the fire is projected into the room and an increased heat in said room is the result, a 85 great quantity of heat is also thrown into the room from the rear of the heater, the same escaping under the screen and through the openings thereof.

I am aware that it is not new to construct 90 a fire-place heater with heating-drums within the jacket thereof; neither is it new to provide a stove with an ornamental screen, and such I do not claim.

Having thus described my invention, what 95 I claim as new, and desire to secure by Letters Patent, is—

A fire-place heater having drums alongside of and in front of the rear line of the body of the stove, and provided with a jacket connected with the body of the stove on a line in the rear of the front line of said drums, all substantially as and for the purpose set forth.

JAMES SPEAR.
